ATTORNEY

UNITED STATES PATENT OFFICE.

HOMA YAMASAKI, OF WHITEFISH, MONTANA.

RAIL-ANCHOR.

1,284,024.

Specification of Letters Patent.

Patented Nov. 5, 1918.

Application filed February 12, 1918. Serial No. 216,747.

To all whom it may concern:

Be it known that I, HOMA YAMASAKI, a subject of the Emperor of Japan, residing at Whitefish, in the county of Flathead and 5 State of Montana, have invented certain new and useful Improvements in Rail-Anchors, of which the following is a specification.

This invention relates to rail anchors and has for its object the production of a simple 10 and efficient rail anchor, which is adapted to engage one of the rails of a track intermediate the joints thereof at a point opposite the rail joint of the opposite parallel rail, for the purpose of preventing ties from being 15 shifted at an angle to each other, under the action of the wave motions caused by a train passing over the rails.

Another object of this invention is the production of a simple rail anchor which 20 includes a minimum number of parts and which may be very easily attached to a rail and anchored upon a pair of parallel ties for holding the ties extending under a rail joint in parallel relation.

With these and other objects in view this 25 invention consists of certain novel constructions, combinations and arrangements of parts as will be hereinafter fully described and claimed.

30 In the drawings:-

Figure 1 is a top plan view of a portion of the railroad track, showing the rail anchor in position.

Fig. 2 is a section taken on line 2—2 of 35 Fig. 1,

Fig. 3 is a section taken on line 3—3 of Fig. 1,

Fig. 4 is a section taken on line 4—4 of Fig. 1,

40 Fig. 5 is a detail perspective view of the anchor plate.

When a train is passing over the rails, the train causes wave motions upon the rail in the direction of travel of the train. This 45 wave motion of the rails will cause the ends of the rails at their joints to shift longitudinally and in view of the fact that the abutting ends of the rails are connected by means of a rail joint 1 as shown in Fig. 1, 50 and also in view of the fact that the rail joint 1 is attached to the ends of two parallel ties, the ties which are engaged by means of the rail joint will also be gradually shifted out of parallel relation with the 55 remaining ties. In order to avoid this inconvenience, there is provided, by means of the

present invention an anchor plate 2 as shown in Figs. 1 and 5 of the drawings, which is adapted to engage the opposite rail with respect to the rail joint above referred to and is 60 placed at a point directly opposite the rail joint of the opposite rail. This anchor plate is then firmly secured to the opposite ends of the ties 3 which support the rail joint 1 and in this manner firmly holds the ties 3 in 65 parallel relation not only with themselves but also with the remaining supporting ties of the track.

It of course is obvious that the rails are laid in the usual manner, the joints of the 70 parallel rails being arranged in staggered relation.

By referring particularly to the special construction of the anchor plate 2, it will be 75 seen that this anchor plate is formed from a blank sheet of metal, such for instance as a single sheet of steel. The anchor plate 2 comprises an elongated plate 4 which elongated plate 4 is provided with an overhanging folded flange 5, the flange 5 being 80 bent flat upon the plate 4, as clearly shown in Figs. 3 and 5 of the drawings. The plate 4 is provided with a centrally arranged laterally extending web 8 which web 8 is provided with a thickened portion 9 upon the bottom 85 thereof, for the purpose of reinforcing the web 8. The web 8 terminates at its outer end in an upwardly extending rail engaging flange 10 having an overhanging bead 11 formed upon the upper edge thereof, and extending inwardly over the web 8.

The plate 4 and overhanging flange 5 are each provided with a plurality of spike receiving apertures or notches 12 which are arranged to register with each other as 90 shown clearly in Fig. 5, for the purpose of permitting spikes 13 to be driven therethrough, in order to anchor or secure the anchor plate 2 in engagement with the ties 3.

A tie plate 14 is carried by each tie 3 and extends under the center of the rail 15 as shown in Fig. 4 and this tie plate 14 is provided with a suitable aperture 15' through which aperture 15' extends the securing spike 16, for the purpose of engaging the rail 15 and also holding the tie plate 14 in engagement with the ties 3. Each plate 14 is also provided with suitable apertures 17 which are adapted to receive suitable spikes 110 13, the spikes passing through the last mentioned apertures engaging one side edge of

the rail base, and the spikes 16 passing through the aperture 15' engaging the opposite side edge of the rail base.

It should be understood that a plate similar to the plate 14 is carried upon each end of each tie and that the apertures through which the spikes 13 pass and which are formed in the plate fitting under the plate 4 are adapted to register with the notches 12 formed in the flanges 5 thereof.

By considering Fig. 1 of the drawings, it will be seen that the web portion 8 is adapted to project between the parallel ties 3, the ends of the plate 4 resting upon the parallel ties 3 and being held in engagement with the rails 15, the flange 10 and overhanging bead 11 engaging one side edge of the base of one of the rails 15. The edge 6 of the overhanging plate 5 engages the edge, or opposite edge, of the rail 15 with respect to the flange 10, the rail being held in engagement with the plate 4 and overhanging flange 5 by means of the spikes 16. These overhanging flanges 5 project over the ends of the plates 14 as shown in Figs. 1 and 4 of the drawings.

From the foregoing description, it will be seen that a very simple and efficient means has been produced for firmly anchoring the center of a rail upon supporting ties at a point directly opposite the rail joint of the parallel or opposite rail whereby the ties which support the rail joint will be held against angular shifting movement.

When it is desired to attach the anchoring plate 2 to the rails, the tie plates 14 are moved or shifted slightly to the position shown in dotted lines in Fig. 1, after the spikes 16 are removed therefrom. The plate 4 and flange 5 may be then extended under the rail 15 in order to cause the overhanging bead 11 carried by the flange 10 to interlock with one side edge of the base of the rail 15. As soon as the bead 11 engages the base of the rail 15, the web 8 may be forced up against the lower face of the rail thereby causing the edge 6 of the overhanging flange 5 to firmly engage the opposite edge of the base of the rail 15. The tie plate 14 may be then moved to its original position, shown in full lines, and the spikes 13 and 16 may be driven into the ties 3, for the purpose of firmly anchoring the plates 2 and 14 in engagement with the ties.

It should be of course understood that certain obvious detail mechanical changes may be made in the present device without

departing from the spirit of the invention, so long as these changes fall within the scope of the appended claims.

60

What is claimed is:—

1. An anchoring plate comprising a body formed from a single sheet of material, said body comprising a side plate, a flange secured to said side plate and overlapping the same and having its edge flush with the inner edge of said plate, a web extending laterally from said plate and adapted to extend across the bottom of a rail, said web provided with an upwardly extending flange, terminating in an overhanging rail engaging bead.

2. In combination with a rail, a plurality of tie plates extending under said rail, of an anchoring plate comprising an elongated rail engaging plate adapted to engage the edge of said rail, means for securing the ends of said plate in engagement with a pair of supporting ties, said plate adapted to extend over a pair of supporting ties, and a rail engaging web secured to said plate and extending under the bottom of said rail.

3. In combination with a rail, a plurality of tie plates extending under said rail, of an anchoring plate comprising an elongated rail engaging plate adapted to engage the edge of said rail, said tie plates provided with a plurality of spike receiving apertures, said rail engaging plate provided with notches formed in one side thereof and adapted to register with some of said apertures formed in said tie plates for receiving a securing spike and holding said plates in engagement with a rail.

4. In combination with a rail, a plurality of tie plates extending under said rail, of an anchoring plate comprising an elongated rail engaging portion adapted to engage the side edges of said rail, said plate provided with an intermediate web extending under said rail and provided with an upturned edge engaging the opposite edge of the base of the rail, and said elongated rail engaging plate overhanging said tie plates and constituting an efficient means for facilitating the connection of said rail engaging plate to said tie plates.

In testimony whereof I affix my signature in presence of two witnesses.

HOMA YAMASAKI.
